HOIST ATTACHMENT FOR JACKS

Filed Oct. 11, 1947

UNITED STATES PATENT OFFICE

2,585,856

HOIST ATTACHMENT FOR JACKS

James Schmieder, Austin, Minn.

Application October 11, 1947, Serial No. 779,319

2 Claims. (Cl. 254—2)

1

This invention relates to hoist attachments for large jacks.

In garages and automotive repair shops and many other places it is a problem to vertically lift heavy objects where there is only limited clearance and where it is impossible to get a direct vertical pull due to the fact that a structure has been built around the article to be lifted and completely covers the same.

It is an object of my invention to provide a hoist attachment for jacks which will permit lifting heavy objects vertically where it is impossible because of overhanging structure to get a direct vertical pull on said object.

It is another object of my invention to provide a novel and improved hoist attachment for a large jack which is extremely simple and inexpensive to manufacture while at the same time is highly efficient in operation.

More specifically, it is an object to provide a hoist attachment for large jacks having a boom with a horizontally disposed forwardly extending element adapted to have its outer end moved over a heavy object to be lifted even though only limited clearance is available above said object whereby said object may be raised and moved from one position to another.

These and other objects and advantages of my invention will more fully appear from the following description made in connection with the accompanying drawings, wherein like reference characters refer to similar parts throughout the several views and in which:

Figure 1 is a side elevational view of my attachment mounted on a wheeled jack showing the boom in lowered position in full lines and in raised position in dotted lines;

Figure 2 is an end elevational view of the device illustrated in Figure 1.

As illustrated in the accompanying drawings, I show a large wheeled jack such as the hydraulically operated jack 5 having a hydraulic cylinder 6 and extensible element 7 with a horizontal platform 8 mounted at the forward end of said extensible member 7. A suitable jack frame 9 is mounted on wheels and carries the hydraulic cylinder 6. The extensible member 7 is pivotally connected to an intermediate portion of the frame 9 as by the pin 10 and the forward end of the hydraulic pumping cylinder 6 has a projectable rod actuated by the piston in said cylinder 6 and is connected to the extensible member by the link 11 at a point a substantial distance below the pivot 10. Operating handle 12 is pivoted to the frame 9 by the stub shaft 13, to which

is fixed a rocker arm 14 which is adapted to mechanically actuate said hydraulic pumping cylinder 6, said rocker arm being connected to the rear end of the piston working in said cylinder as by the link 15. A suitable valve structure (not shown) prevents the back flow of fluid during the pumping operation and may be opened or closed by the jack operator.

My hoist attachment comprises a boom 16 curved at its intermediate portion to form the substantially horizontal forwardly extending boom element 16a and an angularly disposed rear element 16b. The rear lower end of boom element 16b is pivotally mounted on the rear portion of jack frame 9. A pair of jack mounting brackets 17 are fixed to the jack frame 9 in transversely opposed relation and are pivotally connected to a pair of boom brackets 18 as by the pivot pin 19.

An elevating strut 20 has its upper extremity fixed to an intermediate portion of said curved boom 16 and in the form of my invention illustrated this connection is made at the point where the boom curves outwardly to form the horizontal forwardly extending member 16a. The strut 20 is made up of two parallel steel bars in the form shown, but could conceivably be made in a great number of ways. A transverse footing 20a is fixed to the bottom of said parallel bars and extends outwardly beyond the sides thereof. This footing in normal lowered position is adapted to abut the rear portion of the horizontal platform 8 and slides forwardly thereon as the platform 8 is raised. The strut 20 has a bend in the intermediate portion thereof and a brace 21 is connected therewith substantially adjacent said bend and extends substantially horizontally rearwardly therefrom to have its rear end connected to an intermediate portion of the normally sloping boom element 16b.

Means for attaching an object to be lifted are supplied at the free end of boom 16, such as the hook 22 adapted to receive and carry a chain or cable 23 which is fixed to an object to be lifted, such as an engine for a bus or automobile, as shown in Figure 1 and designated by the letter A.

The following is a description of the operation of my jack hoist. My device is well adapted to many uses and a typical example of these uses is the removal of engines from engine-in-the-rear buses and the like. With such buses it is very difficult to remove the engine by use of a vertically operated pulley hoist due to the fact that the bus structure completely covers the engine. My horizontally extending boom can be

moved under the body portion of the bus to overlie the engine and the hook 22 attached to a chain which has previously been fixed to the top of said engine. The engine is then raised up from its mountings a sufficient distance to enable it to be pulled out through the opening at the rear or side of the bus. As the hoist is raised the strut footing 20a slides forwardly on the top surface of the platform 8 and swings the free end of the boom upwardly, the jack being operated in the conventional manner. Thereafter the jack hoist assembly with the engine attached thereto is rolled back away from the bus and the engine thereby removed therefrom.

The fact that an easily movable hoist is provided which is also adapted to carry an object while said object is being moved from one position to another makes this type of jack hoist particularly adapted to small garages and the like. It is a particular advantage to have a movable hoist which is not confined within any particular limits such as overhead box cranes and the like. Also, my jack hoist costs only a small fraction of the price that must be paid for these more complicated box cranes and overhead hoists.

All garages are equipped with a jack similar to the one illustrated to which my boom could easily be attached to provide the hoist as previously described. Thus, it would be possible for small garages and the like to purchase this hoist attachment whereas they could not afford to put in the more expensive overhead cranes, which, in fact, are not as flexible in their possible uses as my hoist and cannot easily be used to remove heavy objects from under overhanging structures, a use to which my hoist is particularly adapted.

It will be seen that an extremely simple yet highly efficient hoist attachment for large jacks has been provided which will enable heavy objects to be removed from overhanging structures, as has previously been described.

It will, of course, be understood that various changes may be made in the form, details, arrangement and proportions of the parts without departing from the scope of my invention.

What I claim is:

1. In combination with a wheeled jack having

a frame and a vertically extensible member with a flat surface at the top thereof, a hoist attachment comprising an A frame, the lower end of one leg of said A frame being pivotally mounted on said jack frame and the other leg of said A frame slidably engaging the flat horizontal top surface of said extensible jack member, a horizontally disposed boom element having its rear extremity fixed to the apex of said A frame, said extensible jack member tilting said A frame on its pivotal connection with said jack frame to controllably raise and lower said horizontal boom element, and means for attaching an article to the free end of said boom element to be raised and lowered therewith.

2. A hoist attachment for a wheeled jack of the type having a rigid frame structure with a vertically shiftable element mounted thereon, said attachment comprising as essential elements only, a boom adapted to be pivotally connected to the frame of the jack, rearwardly of the vertically shiftable element of said jack, an elevating strut fixed in downwardly extending relation to an intermediate portion of said boom, means for making said strut member rigid relative said boom, the lower end of said strut being adapted to engage the vertically shiftable element of said jack with freedom for horizontal sliding movement thereon when said vertically shiftable element is raised and lowered to raise and lower the outer end of said boom, and means for attaching an article to be lifted to the free end of said boom.
